Inventor:

Andrew Flannigan.

United States Patent Office.

ANDREW FLANNIGAIN, OF TRAPPE, MARYLAND.

Letters Patent No. 77,366, dated April 28, 1868.

IMPROVEMENT IN ICE-BREAKERS.

The Schedule referred to in these Letters Patent and making part of the same.

TO ALL WHOM IT MAY CONCERN:

Be it known that I, ANDREW FLANNIGAIN, of Trappe, in the county of Talbot, and State of Maryland, have invented a new and useful Improvement in Ice-Breakers for opening channels in ice-bound harbors, canals, &c.; and I do hereby declare the following to be a full and exact description thereof, reference being had to the accompanying drawings, forming a part of this specification, in which—

Figure 1 is a plan view of my improved ice-breaker.

Figure 2, a side elevation; and

Figure 3, a vertical central longitudinal section thereof.

Similar letters indicate like parts in each of the figures.

The nature of my invention consists in the combination of projecting stay-beams with the front of a suitably curved ice-breaker, and also in the combination, with such beams, of cutting-blades of peculiar construction, as hereinafter described.

Heretofore the various forms of ice-breakers, for opening harbors and navigable streams, have all been constructed with a view of breaking the ice, either by running under the same and lifting it by means of the momentum of the vessel, in combination with its buoyancy, or else by running up upon the ice, and crushing it down by the sheer weight of the vessel and of the breaking-apparatus. In either case the means resorted to for breaking the ice causes much if not all of it to pass and be left floating in the opened channel. This floating ice obstructs the movements of the ice-boat itself, and also quickly knits and congeals together again under the influence of the frost, if left undisturbed. Moreover, the strain upon ice-boats operating either to lift or break the ice, as has just been described, is so great that very strong and powerful vessels, which can only be built at a great cost, are required.

The object of my invention is to so construct an ice-breaking apparatus as that it will operate to open a channel-way and leave it entirely free from ice, and which shall work with such ease that it may be employed with any staunchly-built steam-vessel, or be worked by horse-power, independently of a vessel, in canals, and in all situations which will admit of a footing for draught-animals.

My improved apparatus consists of a deflecting-frame, A, made strong and solid, of suitable timbers, properly stayed and supported by bolts and braces of wood or iron. This frame is made of the width desired in the channel to be opened thereby through the ice. It is formed with a sharp front edge, w, from which a central ridge, a, figs. 1 and 2, inclines rearwardly at an angle of from about twenty to thirty degrees. The frame slopes away with an easy, gentle curve from this ridge down to an edge on either side.

Where the deflecting-frame A is to be used in combination with the bow of a vessel, B, fig. 2, the rear part thereof is so constructed as to leave an open space, b, fig. 1, coinciding exactly in its outlines with the lines of the said vessel's bow, so as to fit and embrace the same closely. The ridge a of the frame, in such case, terminates at the point from whence the open space starts, so as to fit against the prow of the vessel when combined therewith, whilst the sides, S S, of the frame (which is in all cases made wider than the vessel) extend back sufficiently to give a firm, secure support thereto, (see fig. 2.) These sides S S are made to narrow from a point about the centre of the frame, rearwardly, and are protected by guard-beams F F, of wood or iron, which may also be continued along the entire length of the vessel B. The projecting sides S S of the frame are made to extend out beyond the paddle-wheels, where the vessel is propelled by such wheels, to protect them from the ice. The deflecting-frame A, built solidly, as described, is heavily planked and sheathed.

Stay-beams or finger-beams, D, of wood or iron, are also firmly secured to the side edges of the frame, so as to project forward therefrom, just above its water-line, leaving an open angle between their lower sides and the front edge of the frame, at the juncture of the two. Hence, when the frame is properly secured to the bow of a vessel, B, these finger-beams, D, will project over and rest upon the surface of the ice, C, while the front edge, w, of the deflecting-frame A, will incline down under it, as illustrated in fig. 2.

Thin steel or iron plates, E E, are secured to the sides of the frame, in the angle at the juncture of the

finger-beams D with the deflecting-frame A. These plates are cut back, both from the lower side of the beam D above, and from the edge, *w*, of the frame below, to a central line between the two, into angles or offsets, forming teeth *e e*, these teeth being set forward so as to chisel successively a groove through the ice, both on the upper and lower sides thereof, as the frame is forced against it. A sheet of ice, of the width of the front of the frame, is thus cut, which, forced by the forward movement of the frame up its inclined surface, will break on the angular ridge *a*, and dividing into cakes, will slide off down its curved sides S S, and be thrown off upon the unbroken ice on either side.

The projecting finger-beams D, in connection with the front edge, *w*, of the frame A, will prevent the frame from passing under, or riding up on to the ice against which it is impelled, and will keep it steadily in position against its edge, so that the cutting-teeth shall take hold thereof fairly and easily.

The same devices, by steadyng the frame, render any rear attachment thereto unnecessary in its operations, so that it may be used independently of a vessel, and instead of being propelled thereby, be drawn forward by horses or other motive-power, by means of ropes, G G, fig. 1.

I contemplate placing cutting-blades or teeth upon the central ridge *a* of the frame, to facilitate the division of the sheets of ice thrown up thereon.

Although the apparatus may be constructed as an independent machine, to be propelled by the bow of a steam-vessel, or to be drawn by horses, I contemplate constructing in this manner the forward part of a steam-vessel, built expressly as an ice-boat.

Having thus fully described my improved ice-breaking apparatus, I claim therein as new, and desire to secure by Letters Patent—

Projecting finger-beams D D; combined with the front edge, *w*, of an inclined frame, A, on either side thereof, and with cutting-blades arranged at their intersection with said frame, and operating to cut the ice on the upper and lower sides thereof, all substantially as and for the purpose herein set forth.

The foregoing specification of my improved ice-breaker, signed by me, this fourteenth day of February, A. D. 1868.

A. FLANNIGAIN.
